UNITED STATES PATENT OFFICE.

JOSEPH SPRINGARD, OF TRENTON, NEW JERSEY.

AWNINg-SUPPORT.

SPECIFICATION forming part of Letters Patent No. 726,583, dated April 28, 1903.

Application filed October 13, 1902. Serial No. 127,059. (No model.)

To all whom it may concern:

Be it known that I, JOSEPH SPRINGARD, a citizen of the United States, residing at Trenton, in the county of Mercer and State of New Jersey, have invented certain new and useful Improvements in Awning-Supports; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in awning-supports for use on boats, and has for its object to provide a simple and efficient device by means of which an awning may be readily lowered when the boat is about to pass 20 a bridge.

In the drawings, Figure 1 is a side view of the side of a boat and of my device. Fig. 2 is a view of the device as seen fore and aft. Fig. 3 is a side view showing the position of 25 the parts when the awning is lowered. Fig. 4 is a section on the line 4-4 of Fig. 1.

Referring specifically to the drawings, 5 indicates the side of a boat, to which are secured cleats 6 and 6^a to embrace the post 7. 30 This post is split longitudinally for a portion of its length to form a long and a short section 7^a and 7^b, respectively, which are joined by a hinge 7^c to fold in a vertical plane. The short section 7^b is pivoted to the side of 35 the boat and the cleat 6 by a bolt 6^b. The long section 7^a is held in vertical position by a removable pin 8, extending through the cleat at the lower end of the section and into the side of the boat. If desired, the pin may 40 be extended through the upper cleat 6^a. By this means both sections are securely held in upright positions.

The awning is secured to the upper end of the section 7^a in any suitable manner, and 45 when it is desired to lower the same to pass a bridge or for any other reason the pin 8 is removed, which permits both sections to be swung downward, as shown in Fig. 3, the short section turning on its pivot and the 50 long section on the hinge. It is to be understood, of course, that these posts are secured to both sides of the boat, the awning being stretched between them and their number depending on the size of the awning.

55 It will be seen that when the post is upright

it is joined to the side of the boat at two points—the pivot and the removable pin. Consequently it cannot turn in the pivot until the pin is removed. When it is lowered, the awning may be retained in the same position 60 with respect to the length of the boat—that is, it drops straight down. This is advantageous in some circumstances. For example, with a boat having fore and aft cabins and an awning between the awning will drop between the cabins, whereas if one-piece posts were used, pivoted at the bottom to be laid down, the awning would have a fore-and-aft motion, which might cause it to come against one or the other of the cabins. Furthermore, 70 this straight drop is permitted without dropping the post through the deck under a low gunwale. It will be seen from Fig. 3 that the shorter section can be pivoted close to the deck, yet the post will fold to drop the awning close to the gunwale without bringing any part of the post below the pivot.

Having thus described my invention, what is claimed as new, and desired to be secured by Letters Patent, is—

1. The combination with a support, of a post formed in two sections hinged together, one section being pivoted to the support and the other detachably joined to the support, substantially as described.

2. The combination with a support, of a post split longitudinally for a portion of its length, into two sections of unequal length hinged together, the shorter section being pivoted to the support, and the other being 90 detachably fixed to the support, substantially as described.

3. The combination with a support, of a post formed of a long and a short section hinged together, the short section being pivoted to the support and the long section being detachably connected to the support, and a retaining-cleat on the support for the post when in upright position, substantially as described.

4. The combination with a support and a post pivoted thereto, of an extension hinged to the post, and detachably joined to the support, substantially as described.

In testimony whereof I affix my signature 105 in presence of two witnesses.

JOSEPH SPRINGARD.
